UNITED STATES PATENT OFFICE.

SAMUEL M. HERBER, OF INZA, MISSOURI.

REVOLVING RETORT FOR DISTILLING OIL.

1,227,560.

Specification for Design.

Patented May 22, 1917.

Application filed September 26, 1916. Serial No. 122,236.

To all whom it may concern:
Be it known that I, SAMUEL MADISON HERBER, a citizen of the United States, residing at Inza, in the county of Buchanan and State of Missouri, have invented certain new and useful Improvements in Revolving Retorts for Distilling Oil; and I do hereby declare the following to be a full, clear, and exact description of the invention, such as will enable others skilled in the art to which it appertains to make and use the same.

My invention relates to oil distillation and more particularly to a special form of retort which I employ in order to accomplish the most desirable results, my object being to provide a reliably efficient form of rotatable retort and coöperating domes with means intermediate the retort and dome to provide the requisite degree of resiliency to thoroughly compensate for all vibrations or relative movement of the retort and the dome whereby the connections between the retort and dome will at no time be under undue strain which might cause leakage of the substances passing from the retort to the dome and from the dome back to the retort incident to the process of distillation.

With the foregoing and other objects in view it will be seen from the following specification considered in connection with the accompanying drawings that I have provided a special method of mounting my rotatable retort whereby it will be reliably carried upon track ways or riding rings and rollers, wheels or other form of anti-friction carriers in such a manner that when operatively connected to the dome there will be a free yielding action of the connecting parts which will insure against undue strain, inasmuch as a full compensation is afforded by the special manner of mounting my retort, against all undue strain and injury to said connecting parts.

In a former application filed by me viz: Serial No. 44,299 I have shown a rotatable retort operatively connected to stationary domes while in another application filed by me on April 5, 1916, Serial No. 89,035 I have provided a rotatable retort and resiliently mounted domes and in both of said applications I have provided annular track ways of ordinary construction surrounding my rotatable retort, but I desire to call particular attention in this application to the

special form of annular track way or riding ring for my rotatable retort inasmuch as I will show in this application a riding ring of special construction whereby my rotatable retort will be mounted in a thoroughly safe and efficient manner without reference to the load carried by the retort.

I desire, therefore, in this application to call particular attention to the details of construction of my annular track way or riding ring which I preferably provide one for each end of my retort and another for the middle section thereof as shown in the drawings, though it will be understood that should the rotatable retort be unduly lengthened, any desired number of riding rings or annular track ways may be provided with suitable supporting carrying wheels or rollers.

In the accompanying drawings, which are made a part of this application,

Figure 1 shows a longitudinal part sectional view of my rotatable retort and coöperating domes operatively mounted in their respective working positions.

Fig. 2 is a central sectional view of one end of my rotatable retort and contiguous parts.

Fig. 3 is a transverse central sectional view of the retort as mounted and on substantially the same scale as Fig. 2.

Fig. 4 is an end view partly broken away showing one sprocket tooth in position.

Fig. 5 is a perspective view of one of the segments or sections of the sprocket wheel or flange.

Fig. 6 is a perspective sectional view of a portion of my annular track way or riding ring.

Fig. 7 shows one section or segment of the carrying and reinforcing flange disposed intermediate the riding ring and periphery of my retort.

Fig. 8 is a sectional view of said part shown in Fig. 7 as mounted on the retort, and also showing a sectional view of a contiguous part of the wall of my retort.

In order to conveniently refer to the various features of my invention and coöperating accessories, numerals will be employed, the same numeral applying to the corresponding parts throughout the several views.

Referring in detail to the drawings, 1 represents my rotatable retort which may

be made in any desired manner having suitable end sections 2 with manholes 3 if desired and also having a suitable housing 4 with discharge vents or flues 5 for the products of combustion arising from the combustion chamber 6, the latter being formed in any preferred way as by the supporting walls 7 or equivalent means. If desired grate bars 8 may also be provided, 10 said grate bars being supported in any desired way. Thus, any suitable form of fuel may be employed, but preferably the retort is heated by means of the liquid or gaseous fuel pipes 9 suitably mounted in the combustion chamber above the grate bars 8.

Within the housing 4 thus or otherwise provided, I rotatably mount my retort upon the grooved carrying wheels 10 having the journals 11 disposed in the bearing blocks 20 12, each of the said grooved carrying wheels being adapted to be moved laterally in its bearings as will be hereinafter referred to.

I now wish to call particular attention 25 to the fact that I have provided a riding ring or annular track way for my rotatable retort, said carrying rings being multiplied in number as deemed productive of the best results, though it is thought that 30 for ordinary practical purposes three will be amply sufficient, one at each end and one at the middle portion of the retort as shown in Fig. 1 of the drawings. Inasmuch as my retort well charged with oil 35 incident to the operation thereof will possess great weight, it is very desirable and important and in fact at all times absolutely necessary that the weight shall not come directly upon the walls of the retort 40 and in order to obviate the necessity of doing so I have provided a special form of construction for my riding ring or track way wherein it will be observed that I have first secured to the walls of my retort exteriorly, the reinforcing carrying flange or 45 pad, which is preferably built up of a plurality of sections 14 as shown in Fig. 7, and these sections are properly riveted or otherwise secured to the peripheral face of 50 the retort, preferably near the ends thereof and in the middle portion, and said flange thus built up of segments is utilized as a support for my carrying ring or track way proper, which is preferably formed in two 55 complementary sections and properly bolted or otherwise secured to the flange 14, though a solid ring may be provided for each end section if desired.

My riding ring or track way is formed 60 with the annular body portion 15 having the inwardly extending flange 16, near the central portion thereof, the latter being adapted to be bolted to the outwardly extending flange of the segmental reinforcing ring 14 as by passing bolts through the

openings 17 designed to register with the openings 18 in the flange 16 as more clearly shown in Fig. 2 of the drawings. The body portion 15 is also provided with a right angled flange 19, which extends outwardly 70 or radially from the retort and to the peripheral edge of the flange 19, I secure, preferably by a plurality of bolts or screws 20, the lip 21, or if desired, said lip may be formed integral with the flange 19. 75

On the outer face of the body portion 15 I also form at the central portion thereof or directly opposite the flange 16, the rib 22 which is designed to fit into the groove provided in the carrying wheel 10, above 80 referred to.

To the edge of the body portion 15 opposite the flange 19 I secure a plurality of segmental members as shown in Fig. 5 and comprising the body portion 23 each having 85 a tooth or teeth 24, the said body portion being secured by suitable locking screws 25 extending through the openings 26 when registered with the openings 27 as will be clearly obvious. When the proper number 90 of segmental members 23 have thus been bolted to the outer edge of the body portion or plate 15 a complete sprocket wheel is thus provided by means of which my retort may be freely rotated in either direction from any suitable source of power. 95

It will be understood that the lip 21 is designed to project laterally inward, thereby fitting in a recess 28 formed in the contiguous part of the end of the housing 4 and 100 as the free edge of the plate 21 fits snugly into said recess the products of combustion are prevented from escaping at this point.

By reference to Fig. 8 and other views it will be seen that the plurality of segments 105 as shown in Fig. 7 tend to strongly reinforce the walls of the retort at this point inasmuch as the plurality of angle plates when united together form a practically continuous ring around the retort at this 110 point and thereby impart great strength and rigidity to the walls which will enable the retort to be freely rotated in either direction whether partly or completely filled. It will be understood that the joints of the 115 several members 14 are to be broken with or overlapped by the flange 16 when assembled in their operative position, thus insuring great rigidity and strength. Obviously the length of the retort will vary under contraction and expansion incident to the use or nonuse of the retort and in order to properly and fully compensate for any change in the length of the retort I have so mounted the grooved carrying wheels 10 that they 120 may be bodily moved laterally in either direction by the annular ribs 22, thus at all times insuring a reliable support for the retort whether greatly lengthened incident to high temperature or relatively shortened 130

when not in use. As in other applications filed by me I have provided suitable means to deliver the oil or steam into the retort and permit the escape of gaseous products 5 from the retort into the domes out through the trunnions and also provided for the return of the heavier products escaping into the dome, whereby the said heavier products may fall freely back into the retort and 10 since I have fully described in detail in other applications how this can be accomplished I deem it unnecessary in this application to refer specifically thereto.

It will be seen that I have provided suitable 15 form of supporting standards 29 for the domes and a flexible or yielding connection between the domes proper and the rotating still, said flexible connection being of any preferred character as the expansion 20 joint, indicated by the numeral 30.

I have furthermore provided suitable 25 supporting and reinforcing guiding wheels 31 properly mounted in any desired and suitable manner and obviously the purpose 25 of said wheels is to hold the retort from having undue play or lateral movement upon the carrying wheels 10.

I desire to call particular attention to the 30 construction and the method of mounting my carrying rings or annular track ways 35 inasmuch as it will be observed that a plurality of segmental members 14 may be readily provided as by forging, casting or otherwise, requiring no absolutely perfect 40 accuracy and when they are properly secured at proper points upon the peripheral face of the retort the track way proper, preferably formed in two sections, though it will be understood may be formed in one 45 piece is properly disposed in position relative to the outwardly extending flanges of the segments previously secured to the retort, when suitable holes in the flanges 14 may be formed to register with suitable 50 holes previously provided in the inwardly directed flange 16 and said parts are reliably secured by suitable bolts or rivets.

It will also be obvious that the carrying 55 ring or annular track way may be first properly trued, as in a suitable lathe upon its outer surface whereby when placed in position upon the retort, the exterior surface of the ring designed to coöperate with the carrying wheels 10 will cause the retort to rotate truly and without jar or undue vibration.

I have thus provided the specific form of carrying rings and means of anchoring the same for the reason that it is found impracticable to shrink the carrying ring upon the end of the retort and I, therefore, desire to call particular attention to the specific construction presented for these parts and to cover the same in the following

By means of the foregoing construction for the carrying rings and method of securing the same to the peripheral face of the retort at the desired point or points I am enabled to greatly reduce the cost of 70 building my retort as compared with the more expensive and less satisfactory method of shrinking the carrying rings or track ways directly upon the ends of the retort, or otherwise securing the same in position, 75 while at the same time a maximum degree of strength is also imparted to the walls of the retort as will be required incident to the rotation of the retort and the weight of the 80 contents thereof.

Believing that the advantages, construction and manner of using my invention have thus been made clearly apparent, further description is deemed unnecessary.

What I claim and desire to secure by Letters Patent is:—

1. The herein-described revoluble oil distilling retort having carrying rings, said rings having inwardly directed flanges and outwardly directed flanges, means attached 90 to the peripheral face of the retort for engagement with said inwardly directed flanges, a housing, means interposed between the outwardly extending flanges and the housing to form a sealed joint, for the 95 purpose specified, and means for supporting said rings.

2. In a rotatable oil distilling retort, a housing therefor, in combination with carrying rings or trackways for the rotatable 100 retort, segmental flanges secured to the retort at desired points thereon, means connecting said flanges with said rings whereby the carrying face of the ring will be concentric with the peripheral face of the retort, 105 said carrying rings being provided with outwardly directed flanges, lips connected to the outwardly extending flanges of the rings and engageable with the housing, and carrying wheels engageable with said trackways.

3. The combination with a rotatable oil distilling retort, of a plurality of segmental members attached to the retort, a ring having an inwardly directed flange connected to 115 said segments whereby the outer face of said ring will be substantially concentric with the peripheral face of the retort, a housing for the retort and spaced therefrom, the ring being provided with an outwardly directed flange, means extending laterally inward from said outwardly directed flange and engaging the housing, for the purpose specified, and means engageable with said ring for supporting the retort in its revoluble movement.

4. The combination with a rotatable oil distilling retort, of carrying rings surrounding said retort and concentric thereto, said rings being formed at one side edge with 13

4

outwardly extending flanges, a housing, lips connected to said outwardly extending flanges and engaging said housing, the rings being also formed intermediate of their side edges with inwardly extending flanges, means connecting said inwardly extending flanges to the retort with the rings in concentric relation to the retort, the rings being formed intermediate of their side edges and 10 on their outer peripheries with ribs, grooved carrying wheels in which said ribs are received, and a sprocket connected to the side edge of one of said rings opposite to the edge where the outwardly directed flange of 15 said ring is formed.

5. The combination with a rotatable oil distilling retort, of a housing therefor, and means for supporting said retort in its revolute movement and at the same time allowing for the longitudinal expansion and contraction of said retort, said means consisting of riding rings formed with inwardly and outwardly directed flanges, a plurality of segmental members connected 20 to the retort and fastened to the inwardly directed flanges of said rings, lips connected to the outwardly directed flanges and extending laterally inward into engagement with the housing, said rings being formed 25 on their peripheries with circumferentially extending ribs, grooved supporting wheels upon which said rings are supported and in the grooves of which said ribs are received, and bearings for said wheels in 30 which the wheels are capable of a bodily movement in a direction at right angles to their revolute movement.

6. The combination with a rotatable oil distilling retort, of means for supporting 40 said retort in its revolute movement, said means comprising carrying rings formed with outwardly and inwardly extending flanges, segments connected to the periphery of the retort and to the inwardly extending flanges of said rings, a housing for the retort, and means connected to the outwardly extending flanges of the rings for engage-

ment with the housing to form a sealed joint therewith, for the purpose specified.

7. The combination with a rotatable oil 50 distilling retort, of carrying rings concentrically disposed to the retort and surrounding the same, said rings being connected to the retort and formed with outwardly extending flanges, a housing, means connected to the 55 outwardly extending flanges of the rings for engagement with the housing, for the purpose specified, and a sprocket connected to one of said rings.

8. The combination with a rotatable oil 60 distilling retort, of carrying rings surrounding said retort and concentric thereto, said carrying rings being formed with inwardly extending flanges and with outwardly extending flanges in offset relation to the inwardly extending flanges, a housing, lips connected to the outwardly extending flanges of the rings and engageable with the housing, segments connecting the inwardly extending flanges of said rings and the retort, 70 said rings being formed on their peripheries with ribs, and grooved carrying wheels in the grooves of which the ribs are engaged, as and for the purpose set forth.

9. The combination with a rotatable oil 75 distilling retort, of carrying rings surrounding said retort and concentric thereto, said rings being formed at one side edge with outwardly extending flanges, a housing, lips connected to said outwardly extending 80 flanges and engaging said housing, for the purpose specified, the rings being also formed with inwardly extending flanges, angular segments connecting said inwardly extending flanges to the retort, the rings being formed, in the same plane as said inwardly extending flanges and on the outer peripheries of the rings with ribs, and 85 grooved carrying wheels in which said ribs are received.

In testimony whereof I have signed my name to this specification.

SAMUEL M. HERBER.
